UNITED STATES PATENT OFFICE.

ARTHUR C. ROWE, OF NEW YORK, N. Y., ASSIGNOR TO A. C. ROWE & SON, OF NEW YORK, N. Y., A FIRM COMPOSED OF ARTHUR C. ROWE AND KENNETH P. ROWE.

FIRE-EXTINGUISHER.

1,070,987.

Specification of Letters Patent.

Patented Aug. 19, 1913.

Application filed May 10, 1912. Serial No. 696,435.

To all whom it may concern:

Be it known that I, ARTHUR C. ROWE, a citizen of the United States of America, and a resident of the city, county, and State of New York, (whose post-office address is No. 280 Broadway, New York, N. Y.,) have invented a new and useful Improvement in Fire-Extinguishers, which invention is fully set forth in the following specification.

10 My invention relates to chemical fire-extinguishers of the well-known type that is inverted when brought into use, to bring the chemicals together.

15 The object of my present invention is to provide more efficient means for extinguishing fires.

20 The main features of my invention comprise improved means for governing the admission of the (sulfuric) acid to the region of chemical reaction,—the governing of the admission of the (bicarbonate of soda) solution to the same region,—and the uniformly-regulated generation of the (carbonic-acid) gas.

25 The invention comprises also improved means for discharging the contents when desired, and the various features of construction and arrangement hereinafter pointed out and claimed.

30 The main object underlying my present invention is to deliver upon the conflagration a stream consisting not merely of water or other liquid, but of the liquid containing a much larger proportion than heretofore 35 of the (carbonic-acid) gas,—the gas being itself the most efficient agent in extinguishing fire. This is accomplished by means of the regulated or controlled admission of the acid, and also of the regulated and controlled admission of the soda-solution, to

40 the decomposing-region, so that a fresh supply of the soda-solution (from which the carbonic-acid gas has not been previously released by the action of the acid) shall be 45 continuously supplied uniformly and in proper proportions with the fresh supply of acid that is being continuously fed to the soda-solution in the protected decomposing region,—which region is surrounded

50 with a protecting shield to prevent interference with the chemical action by agitation of the liquid in the outer or main tank,—and at the same time furnish a protected channel for the upward movement 55 of the current. It should be said in ex-

planation that the stream of liquid, from these carbonic-acid gas extinguishers, is the vehicle for conveying the gas to the fire, and is the only means by which the gas can be carried through the air to make it effective at distant points. It is evident, therefore, that to increase the extinguishing power of a given amount of chemicals, everything depends on charging the stream evenly with all the gas that it can carry 60 to the fire, from the first to the last of the throw, so as to utilize this carrying power to its fullest extent. If the stream is only half charged for a part of the throw, the extinguishing power during that time is reduced in the same proportion. If the amount of gas generated during any period be too great, so as to overcharge the liquid, the excess of gas will be lost in transit and wasted, never reaching the fire.

70 The features herein described have for their main object the more perfect control of the chemical action which takes place, in such a way as to realize the maximum extinguishing power which is possible from the chemicals, thus securing a more scientifically regulated handling of the chemicals.

75 In further explanation of the process, it should be stated that the affinity existing 80 between the water and the gas, by which the water is enabled to absorb large volumes of the gas in a highly condensed state, is very much increased by cold temperature and high pressure; and one object of this 85 invention is to cause the larger part of this absorption of the gas by the water at points in the tank where the water is coolest. In the decomposing region referred to, the violent chemical re-action which takes place 90 between the soda and acid causes a rise of temperature of from thirty to fifty degrees; so that by taking advantage of these natural laws by a properly constructed device, the heated water can be made to rise to the top 95 of the tank while the cool liquid naturally takes its place at the bottom, instead of being driven hither and thither throughout the entire contents of the tank, as has heretofore been the case where the chemicals are 100 mixed indiscriminately by the violent agitation that always takes place where no protection is given at the points where chemical re-action is taking place.

105 As will be understood by the foregoing, 110

the coolest portion of the soda-solution must necessarily be at the bottom, *i. e.*, near the region of the exit; while the warmer portions of the liquid will be at the top, *i. e.*, farthest removed from the exit.

5 I have invented an apparatus for carrying out this method of governing and controlling the re-action, and creating the circulation referred to. My process and apparatus 10 will be best understood by reference to the annexed drawings, in which—

Figure 1 is a vertical section through a preferred embodiment of my apparatus; Fig. 2 is a vertical section of a detail, inverted, to show the position of the same when the device is in use; Fig. 3 is a side view of the cage and shield that surround the acid-bottle and the entire decomposing region, part of the shield being removed; 15 Fig. 4 is a horizontal section through the line 4—4 of Fig. 3, looking upward; and Fig. 5 is a transverse horizontal section, on a smaller scale, through the top of the apparatus, with the interior parts removed.

20 1 represents the main receptacle or canister, having the shoulder with the exteriorly-threaded flange or neck 2.

25 3—3 represent two converging wedge-shaped outlet-conduits, which begin at diametrically-opposite positions near the top of the canister (*i. e.*, the exit), and converge to the outlet-nipple 4 (see Figs. 1 and 5). The nipple 4 is shown as a down-turned elbow, upon which is secured the usual rubber-tubing 5, at the end of which is the discharge-nozzle (not shown). The closure of 30 the canister comprises the head 6, having the hand-wheel 7 for operation, and the down-turned flange 8 that is interiorly 35 screw-threaded to engage the thread on the neck 2; and from the bottom of the head 6 depends centrally the screw-threaded stem 40 11. The acid-bottle, the decomposing-cup, the cage, and the shield, are all carried from 45 this depending stem.

50 17 represents a head, having the interiorly-threaded upper member to engage this stem 11, and having the depending flange 18, which (when the apparatus is inverted, as in Fig. 2) constitutes the decomposing-cup. Also depending from the head 55 17 are the (three) guide-arms 19, having the inclined guide-surfaces that terminate in the horizontally-aligned shoulders 20, which latter are located in a plane slightly below the bottom of the cup 18 (or, when inverted, as in Fig. 2, slightly above the level of the cup). A cylinder 21 is disposed concentrically around the head 17, being secured 60 thereto by (three) radial webs 22 (see Fig. 4). 23 is a cylinder of wire-netting whose upper edge is secured to a sleeve 24, and whose lower edge is secured to a ring 25. A concentric cup 26 is carried within this 65 lower ring 25, as by radial-webs 27; while

(three) resilient shouldered holding-arms 28 extend from the sleeve 24 to the cup 26. The sleeve 24 is adapted to telescope over the ring 21, where it is secured in place by the spring-catches 29.

70 30 represents the acid-bottle, and 31 the ball or closure therefor; parts 21—23—24—25 constitute the shield; and parts 26—28 (and 19) the bottle-cage.

To insert the bottle in place (after sufficient acid has been put into it, and after placing the ball 31 upon the mouth thereof), the shield is disengaged from the ring 21, and the bottle placed within the cage and seated in cup 26, there being preferably a 75 weight 34 at the bottom of the bottle; after which the shield (and cage) will be returned to position and properly secured,—guide-arms 19 properly positioning the mouth of the bottle. The function of the weight 32 80 is that when the apparatus is inverted, and much of the acid has passed out, the buoyancy of the partly-emptied bottle will not cause it to float upward, away from the 85 shoulders 20.

90 Heretofore, in devices of this character, when the extinguisher is inverted for use, the acid-bottle is supported upon its shoulders, as at 32 in Fig. 2. But, in the commercial manufacture of bottles in large 95 quantities, there is liable to be a considerable variation in the distance between the shoulder and the lip 33; and this means that there will be a considerable variance in the width of the annular space between the 100 lip and the ball 31 (or other regulating-device). But, by supporting the bottle from its lip 33, upon the seats 20, I insure a uniform adjustment, and thereby a predetermined control of the outflow of the acid. 105

The overhanging flange of cup 18 tends to prevent any of the soda-solution from splashing into the acid-bottle, and the ball 31 particularly insures that none of the solution shall reach the interior of the bottle. 110 So soon as the apparatus is inverted, however, the ball 31 falls away (preferably into the concave seat indicated in the head 17), and the bottle itself drops a slight distance until its lip 33 rests upon the seats 20. The 115 annular opening thus provided furnishes a regulated feed of the acid-contents, and the re-action with the soda-solution takes place within the cup 18. This re-action generates considerable temperature and pressure. The 120 heated liquid tends to rise, within the annular space or channel defined between the bottle-cage and the surrounding shield, and passes out at the top thereof,—while the gas (under increasing pressure) passes out 125 through the interstices and openings therein, and travels along the lines of least resistance (that is, toward the outlets),—meanwhile fresh portions of the soda-solution travel up through the bottom of the chan- 130

nel formed by the shield and into the decomposing-cup,—thus creating a fairly uniform circulation; and the gas, during its passage to the outlets, encounters fresh portions of comparatively cool liquid which (by reason of its greater coolness) will absorb a larger quantity of the gas. The pressure generated forces this gas-saturated liquid out through the converging walls of the outlets 3 further compressing the column of charged liquid, and causes or permits further absorption of the gas. In consequence, the stream emerging from the nozzle carries a much larger proportion of gas and delivers a greater portion of its gas-contents upon the flames.

The wedge-shaped conduits 3 perform a most important function in this process. It will be noticed that instead of being of uniform width and dimensions, as in the case of a pipe that is sometimes placed around the top of such tanks simply to prevent the liquid from slopping out when carried on moving vehicles, these conduits 3 are made 25 with steadily contracting walls from the intake to the point of exit, in order to secure a steadily increasing pressure and hence a more perfect absorption of the gas by the water at the point where it leaves the extinguisher. At this point it should be said in further explanation that three things are desirable in order to secure the best results in charging the liquid with the carbonic-acid gas:—

35 First: Thorough mixing of the gas with the liquid. This is enhanced when the gas, in minute globular form, is pressed through the screened opening at the intake of the conduit, under high pressure.

40 Second: That the temperature of the liquid be as cool as possible. This is secured by placing the intake of the conduits at the region where the liquid is coolest, *i. e.*, near

that end of the tank which is the bottom when the apparatus is inverted.

Third: High pressure. This is secured by passing the stream through the contracting walls of the conduits so that the water and the gas combined can be forced inward through these steadily contracting walls under high pressure where all the conditions are most favorable for complete absorption of the gas by the water.

I have thus described my invention with some particularity of detail, but only for the sake of clearness; since my invention is not limited to the precise construction and arrangement of parts set forth. Parts of the invention may be used to the exclusion of other parts, and modifications of the parts 55 may be resorted to, without in any case departing from the spirit of my invention.

Having thus described my invention, I claim:—

1. In a fire-extinguisher, the combination 65 with a main receptacle, of a detachable cover hermetically sealing the same and having a depending stem, a bottle-cage and a decomposing-cup carried thereby, and a shield surrounding the latter to shut off a protected space open at top and bottom.

2. In a fire-extinguisher comprising a main receptacle containing the acid-bottle as well as the alkali-solution, the combination of a decomposing-cup for the chemical 75 re-action, means for regulating the admission of acid thereto, and a shield surrounding said mixing-cup to shut off a protected space open at top and bottom.

In testimony whereof I have signed this 80 specification in the presence of two subscribing witnesses.

ARTHUR C. ROWE.
